(57) **CLAIM**

We claim the ornamental design for a toy vehicle, as shown and described.

DESCRIPTION

FIG. 1 is a front perspective view of the toy vehicle showing our new design;

FIG. 2 is an overhead plan view thereof;

FIG. 3 is an underside plan view thereof;

FIG. 4 is a side elevation view thereof;

FIG. 5 is an opposite side elevation view thereof;

FIG. 6 is a front elevation view thereof;

FIG. 7 is a rear elevation view thereof; and,

FIG. 8 is an enlarged partial plan view of the textured surface of the toy vehicle shown in FIGS. 1, 2, 6 and 7.

The ornamental design which is claimed is shown in solid lines in the drawings. The broken lines in the drawings are for illustrative purposes only and form no part of the claimed design.
